UNITED STATES PATENT OFFICE.

ROBERT G. EWEN, OF WASHINGTON, RHODE ISLAND, ASSIGNOR TO DEAPER CORPORATION, OF HOPEDALE, MASSACHUSETTS, A CORPORATION OF MAINE.

SELVAGE-LOOP-RETAINING MECHANISM.

Application filed May 12, 1928. Serial No. 277,160.

This invention relates to mechanism for forming a perfect selvage in the weaving of cloth in a loom by means of loop retaining fingers operating one adjacent each selvage in such a manner as to prevent the filling during the weaving operation from being drawn so tightly as to indent the selvage and thus produce an irregular selvage.

The object of the invention is to provide 10 a selvage loop retaining mechanism of a simple and efficient construction, one that is readily operated and not likely to get out of order and one of sufficient strength to withstand the pull of any type of filling, however coarse, 15 and one capable of being employed in cloth woven under a heavy tension.

The object of the invention is further to provide such a mechanism which may be embodied in and supported by the temples 20 uniformly located adjacent the selvage for maintaining the width of the cloth.

These and other objects and features of the invention will appear more fully from the accompanying description and drawings and 25 will be particularly pointed out in the claims.

As the construction employed is preferably the same at each side of the loom, it will be sufficient to illustrate the construction at but 30 one side of the loom and for that purpose the mechanism is shown at the right-hand side.

The selvage loop retaining mechanism of this invention may be carried by any suitable support mounted on the loom frame and located adjacent the selvage forward of the 35 fell, but it is particularly adapted to be carried by the temple and is so illustrated herein. Any form of suitable temple may be thus employed, but for convenience of illustration a temple such as shown in the patent to Har- 40 daker, No. 231,809, August 31, 1880, is shown.

The drawings illustrate a simple and preferred form of the invention carried by the temple, as already noted.

In the drawings:

Fig. 1 is a side elevation of the mechanism 45 with a portion of the lay of the loom shown in cross section.

Fig. 2 is a view generally similar to Fig. 1 looking at the opposite side of the mechanism 50 and with the mechanism chiefly in vertical cross section.

Fig. 3 is a top plan view of the mechanism.

The support for the selvage loop retaining 55 mechanism is shown as a temple having a shank 1 mounted from a fixed portion of the

loom frame, such as the breast beam, not shown, and having a head 2 carrying the usual transversely extending temple roll 3 and located adjacent the selvage forward of the fell of the cloth, all in the usual manner. 60 As noted, the temple may be of any of the usual types.

A portion of the lay 4 of the loom with the reed 5 is shown.

A circular arcuate guiding groove is 65 formed in the support afforded by the temple head for guiding the loop retaining finger. As shown, a block 6 of general L-shape in cross section is mounted on the temple head 2 for this purpose by means of a vertical 70 screw 7 and a horizontal screw 8. This circular arcuate groove 9 is cut into the face of the depending portion of the block 6 which abuts against the inside of the head and extends fore and aft or in the general direction 75 of the selvage with its concave side toward the cloth and thus arched around the temple roll. The other side or wall of the groove is formed by the temple head 2 against which the depending portion of the block 6 abuts. 80

The loop retaining finger has its shank 10 of a similar, circular, arcuate form to fit and slide in the groove 9 and at its rearward end is formed to present a tapering point 11 around which the filling is held. 85

The loop retaining finger is shown as operated by a plunger and a spring. In the construction illustrated, a cylindrical plunger 12 is mounted for horizontal movement fore and aft in the block 6 which is secured to and forms a part of the temple head, the block being bored out to receive the plunger. The plunger and finger are provided with aligned vertical slots, 13 and 14 respectively, opening from their opposed surfaces. A link 15 is 95 pivoted at 16 at one end in the slot 13 to the plunger 12 and at the other end at 17 in the slot 14 to the finger 10. Consequently as the plunger is reciprocated, the finger is moved forward and rearward in its guiding slot. 100

The plunger is shown as normally projected rearward by a helical spring 18 connected at its rearward end to a pin 19 mounted in the block 6 and at its forward end to a set screw 20 which locks a stop collar 21 to the plunger 105 12 and thus limits the rearward movement of the plunger and finger. The plunger is shown as given its forward movement by the contact of the lay with a head 22 on the rear end of the plunger. 110

When the plunger is projected rearward, the stop 21 is adjusted so that the point 11 of the loop retaining finger stands vertical, as shown in Figs. 1 and 3, alongside the selvage, preferably just outside the selvage, although it may stand at any desired position laterally with respect to the selvage. When the plunger is moved to forward position, the finger stands clear of the cloth forward of the fell.

10 The operation of the mechanism will be apparent. Considering the operation at the right-hand side of the loom illustrated, and the lay beating up after the shuttle has been picked into the right-hand box, the lay contacting with the head 22 of the plunger forces the plunger forward carrying with it the loop retaining finger to its forward position clear of the cloth and forward of the fell. After this pick is beaten in, the lay swings back allowing the loop retaining finger projected rearward by the action of the spring 18 to move down behind the filling extending from the selvage to the shuttle. The shuttle then makes the next pick to the left side of the 25 loom, carrying the filling around the finger. As the lay again swings forward to beat in this pick, it again moves the finger to its forward position, withdrawing it from the filling looped around it just before final beat-up 30 takes place. Thus the filling is held by the loop retaining finger until just as it is beaten into the cloth, thus insuring a regular and even selvage.

It will be seen that the loop retaining finger 35 is firmly held and guided in its arcuate guiding slot and supported substantially throughout its length. The operating connections with the plunger afford an easy and accurate movement of the finger. No matter how great the strain of the filling upon the finger may be, the finger will hold the filling and insure the accurate formation of the selvage.

The parts in which the invention is embodied may readily be attached to existing 45 temples and are readily and economically manufactured.

Having thus described the invention, what is claimed as new, and desired to be secured by Letters Patent, is:

50 1. A selvage loop retaining mechanism for looms comprising a support mounted on the loom frame and located adjacent the selvage

forward of the fell, a circular arcuate guiding groove in said support extending in the direction of the selvage with its concave face 55 toward the cloth, a loop retaining finger having an arcuate shank fitting and sliding in said groove and having a point standing vertical alongside of the selvage when the finger is projected rearward and standing clear of the cloth forward of the fell when the finger is moved to forward position, a plunger mounted for horizontal movement in the support above the finger and having a head in the path of the lay, a spring acting normally to project the plunger rearward, and a link connecting the plunger and finger.

2. A selvage loop retaining mechanism for looms comprising the construction defined in claim 1, in which the plunger and finger have aligned vertical slots opening from their opposed faces and in which the link extends into both of said slots and is pivoted at one end to the plunger and at the other end to the finger.

3. A selvage loop retaining mechanism for looms comprising a temple mounted on the loom frame and having a head with a temple roll therein, a circular arcuate guiding groove in the temple head extended fore and aft and arched around the temple roll, a loop retaining finger having an arcuate shank fitting and sliding in said groove and having a point standing vertical alongside of the selvage when the finger is projected rearward and standing clear of the cloth forward of the fell when the finger is moved to forward position, a plunger mounted for horizontal movement in the temple head above the finger and having a head in the path of the lay, a spring acting normally to project the plunger rearward, and a link connecting the plunger and finger.

4. A selvage loop retaining mechanism for looms comprising the construction defined in claim 3, in which the plunger and finger have aligned vertical slots opening from their opposed faces and in which the link extends into both of said slots and is pivoted at one end to the plunger and at the other end to the finger.

In testimony whereof, I have signed my name to this specification.

ROBERT G. EWEN.
